SHOE SOLE

Henry N. Schrage, Los Angeles, Calif., assignor to
The Rubber Corporation of California, Garden
Grove, Calif., a corporation of California

Application December 15, 1950, Serial No. 13,447

Term of patent 14 years

(Cl. D7—5)

To all whom it may concern:

Be it known that I, Henry N. Schrage, a citizen of the United States, residing at Los Angeles, in the county of Los Angeles and State of California, have invented a new, original, and ornamental Design for a Shoe Sole, of which the following is a specification, reference being had to the accompanying drawing, forming a part thereof.

Fig. 1 is a bottom plan view of a shoe sole, showing my new design;

Fig. 2 is a longitudinal sectional view on the line 2—2 of Figure 1; and

Fig. 3 is a transverse sectional view on the line 3—3 of Figure 1.

My design for a shoe sole is characterized by the bevelled margin forming the periphery of the sole, and transverse plateaus rectangular at their raised corners and individually traversed by a plurality of fine grooves.

I claim:

The ornamental design for a shoe sole, substantially as shown and described.

HENRY N. SCHRAGE.
